UNITED STATES PATENT OFFICE.

WILLIAM L. BUEDINGEN, OF MILWAUKEE, WISCONSIN.

MAGNETIC TOY.

Application filed March 11, 1925. Serial No. 14,752.

This invention relates to certain new and useful improvements in magnetic toys and has as a general object the provision of a toy which will be amusing as well as instructive.

It is another object of this invention to provide an improved type of toy having a magnetic base resembling a slate upon which characters may be built with wire or other members of a magnetic material.

A further object of this invention resides in the provision of a toy of the character described which is extremely simple in construction and inexpensive of production.

With the above and other objects in view which will appear as the description proceeds, my invention resides in the novel construction, combination and arrangement of parts substantially as hereinafter described and more particularly defined by the appended claims, it being understood that such changes in the precise embodiment of the hereindisclosed invention may be made as come within the scope of the claims.

In the accompanying drawings, I have illustrated two complete examples of the physical embodiment of my invention constructed according to the best modes I have so far devised for the practical application of the principles thereof, and in which:

Figure 1 is a perspective view of the preferred embodiment of my invention, parts thereof being broken away in order to illustrate structural details;

Figure 2 is a transverse sectional view taken through Figure 1 on the plane of the line 2—2.

Referring now more particularly to the accompanying drawings in which like numerals designate like parts throughout the several views, the numeral 5 designates one half or section of a box or container which may be of cardboard or any material in which the toy may be concealed when not in use and which also provides means for mounting the toy in active position for playing.

Secured in a rectangular frame 6, of a size to fit within the box 5, is a plate 7 preferably resembling a slate and made of sheet metal such as iron or any other material through which the magnetic energy of a magnet 8 can be exerted in the manner to be later described. The magnet 8 in that form of my invention illustrated in Figure 1 is preferably of the horseshoe type and is

mounted in a pocket or recess 9 formed in a support 10. The support 10 may be constructed of cardboard or other material and is folded along a longitudinal line, as at 11, 60 with its upper layer 12 cut away at its outer edge, as at 13, to receive the magnet. That portion of the lower layer 14 adjacent the cut-away part 13 is depressed to provide a magnet receiving recess or pocket 15, the 65 layers being held together by rivets or other fastenings 16.

The lower layer of the support 10 extends beyond the magnet receiving recess so that the overall width thereof is greater than that 70 of the box 5 and when mounted in the box as illustrated in Figure 2 the portion thereof mounting the magnet is inclined upwardly. The board or slate is mounted on the magnet in the manner illustrated and held thereby 75 by its attraction. If the board is of non-magnetic material, it is retained in place by the engagement of its lower edge with the adjacent box side wall.

As will be readily apparent, the influence 80 of the magnet extends through the slate or board 7 to any characters built thereon of magnetic material. In Figure 1 is illustrated an object formed from lengths of 85 wire 18 bent to various shapes together with letters 19 formed from similar material. If desired the characters may be formed from cardboard or other material 20 and have one or more magnetic members 21 secured thereto, see Figures 3 and 4.

When it is desired to collapse the game 90 within the box, the extended portion 17 forming the supporting leg is folded against the pocket portion 15, the slate or game board is then placed in the box, the support 10 placed thereover and the cover, not shown, secured in place. If desired, a suitable bridging member may be extended across the poles of the magnet to preserve 95 its strength in the well known manner.

What I claim as my invention is:

1. In a toy, the combination with a magnetic board, characters formed of magnetizable material and adapted to be placed on the board and a magnet for holding the 105 characters in their desired positions, of a container in which the magnetic board and the magnet are concealable when not in use, a support for the board formed of bendable material one edge portion of the support 110 being engaged in one inner edge of the container when in use, a recess formed in the

- support and receiving therein the magnet, said magnet and support having positioned thereover the magnetic board, and a leg member pivoted to the pocket and engageable with the inner edge of the container opposite the first-mentioned inner edge to secure the support and consequently the board at an angle.
2. A device of the class described, comprising a magnetic board, a magnet for imparting magnetic force to the board, a support for the board and magnet formed from one piece of bendable material and including a flat supporting surface having one edge portion cut to conform with the magnet, an under portion doubled back from the opposite edge of the flat supporting surface, a pocket in which said magnet is positioned formed from said under portion and aligned with the cut in the supporting surface, and a leg member pivotally extended from the pocket and means for engaging the leg and the edge of the supporting surface to secure the support and consequently the board at an angle.
3. A toy of the class described comprising a container, a foldable support within said container and adapted to be maintained at an angle therein, a pocket formed in said support, a magnet receivable within said pocket, a board positioned within said container and resting upon said magnet, and character forming members formed of magnetizable material and adapted to be held on the board by the magnetic influence of the magnet.
4. In a magnetic toy, comprising a container, means cooperating with the container to form a slanting support, a magnet, means mounting the magnet on the support, a board supported by the magnet with its under face adjacent the flat surface of the magnet, and magnetic elements adapted to be arranged on the board to form various characters, said elements being held on the board by the influence of the magnet exerted through the board.

In testimony whereof I affix my signature.

WILLIAM L. BUEDINGEN.
